REVERSING MECHANISM.

No. 833,255.

Specification of Letters Patent.

Patented Oct. 16, 1906.

Application filed June 29, 1903. Serial No. 163,596.

To all whom it may concern:

Be it known that I, CHARLES F. SMITH, of Melrose, county of Middlesex, and State of Massachusetts, have invented an Improvement in Reversing Mechanism, of which the following description, in connection with the accompanying drawings, is a specification, like letters on the drawings representing like parts.

10 The present invention relates to a single pulley-reversing mechanism, such as may be used with lathes and the like, or in any case where a driven member is to be driven in two different directions by a pulley-wheel or gear which rotates continuously in one direction only.

15 It is the purpose of the present invention to arrange a device of this kind so that two different speeds can be obtained in one direction and a single speed obtained in the reverse direction, a further feature of the invention being embodied in an arrangement whereby a single shipper member can be utilized to obtain the desired operation.

20 25 The invention is herein shown as embodied in a lathe counter-shaft driven by an ordinary belt-pulley, it being obvious, however, that the same reversing mechanism can be used with other driving mechanism.

30 35 Figure 1 is a longitudinal section, partly in elevation, of a reversing mechanism embodying the invention. Fig. 2 is a section taken on line x^2 of Fig. 1 looking toward the left; and Fig. 3 is a detail view of a portion of Fig. 1, showing the parts in a different position.

40 45 The pulley a is shown as provided with a hub-bearing portion a^2 , upon which is fixed a gear-wheel a^3 , the said hub having a bearing upon a sleeve b , which in turn bears upon the driving member or shaft c , the pulley a being normally free to rotate on the sleeve b , while the sleeve is free to rotate on the shaft c , the shaft of course being free to rotate within the sleeve if the latter is stationary.

50 55 The sleeve b carries one or more gear-wheels b^2 , three of such gear-wheels being herein shown, Fig. 2, as mounted to rotate upon bearing-spindles b^3 , projecting inward from spider-arms b^4 , which extend radially from the sleeve b . The said gears b^2 are in mesh with the gear a^3 upon the pulley-hub a^2 , and also with an internal gear d^2 , formed on a

sleeve d , which is separate from the sleeve b , but mounted upon the shaft c in a similar manner. The gears b^2 are shown as inclosed in a casing, the internal gear d^2 having a cover portion in the form of a disk d^{20} , having a bearing on the hub a^2 and being fastened to the face of the internal gear member. The intermediate gears, therefore, are completely inclosed in a casing which may be filled with a lubricant.

55 60 Each of the sleeves b and d is arranged to be held stationary or to be connected with the shaft c , the said sleeves being shown as provided, respectively, with friction-disks b^5 and b^6 and d^3 and d^4 , which form clutch members to coöperate, respectively, with disks c^2 and b^{60} , c^3 and d^{40} , the disks c^2 and c^3 being splined upon the shaft c , while the disks b^{60} and d^{40} are held stationary, so as to prevent the rotation of the sleeves b and d when clutched thereto.

65 70 75 As herein shown, the disks b^{60} and d^{40} are supported, respectively, upon the sleeves b and d for convenience in construction and are longitudinally movable thereon, but prevented from rotation by means of loops or straps b^{61} and d^{41} , which firmly hold them without preventing the slight longitudinal movement which is necessary to bring the said disks into frictional engagement with their coöperating members.

80 85 90 As a convenient means for producing the slight longitudinal movement of the clutch members to cause the operation thereof the fixed or stationary members d^3 and d^4 and b^5 and b^6 are provided with levers e , f , g , and h , pivotally connected to the said members, being substantially in the shape of elbow-levers, respectively, having members e^2 , f^2 , g^2 , and h^2 , which engage, respectively, with the shoulders c^4 , d^{42} , c^5 , and b^{62} . The other arm of each lever is arranged to be engaged by a member capable of sliding longitudinally with relation to the shaft c and having inclined surfaces to rock the levers and produce the necessary longitudinal movement of the clamping members. These sliding members are shown as sleeves i and k , mounted, respectively, upon the sleeves b and d and provided with annular channels i^2 and k^2 , which receive forked members i^3 and k^3 , which are mounted, respectively, upon lon-

- itudinally-movable rods i^4 and k^4 . The said rods are normally movable together in a longitudinal direction, so as to slide the sleeves i and k from the position shown, Fig. 5 1, in which they are in engagement with the levers h and e , to a position in which they will engage the levers g and f . In the position shown the disk c^3 , which rotates with the shaft c , is in frictional engagement with the 10 disk d^3 , which is fast upon the sleeve d , so that the said sleeve d and the shaft c are locked together, while the disk b^6 upon the sleeve b is in frictional engagement with the stationary disk b^{60} , so that the sleeve b is 15 prevented from rotation. Under these conditions the support for the intermediate gears b^2 is held stationary, so that the rotation of the pulley a will produce a rotation in the opposite direction of the sleeve d through 20 the agency of the intermediate gears b^2 and the internal gear d^2 , thus causing the said sleeve d to travel in a direction opposite to that of the pulley a and drive the shaft c with it. If, however, the rods i^4 and k^4 are 25 moved in the opposite direction, so as to bring the members i and k into engagement, respectively, with the levers g and f , the sleeve d will be disconnected from the shaft and held stationary through the agency of 30 the disk d^4 and the disk d^{40} , while the sleeve b will be locked to the shaft through the agency of the disk b^5 and the disk c^2 . Under these conditions the internal gear d^2 will be stationary, so that the rotation of the pulley 35 a acting through the intermediate gears b^2 will cause them to roll around the inner periphery of the internal gear and carry with them the sleeve b , to which they are connected, at a lesser speed than that of the pulley, so that the shaft c will travel in the direction of the pulley a , but at a reduced speed. If now it is desired to cause the shaft 40 c to travel in the direction of the pulley a and at a speed equal thereto, it becomes necessary only to lock both the sleeves b and d to the shaft, which is the same as connecting one with the other, so that there can be no rotary movement of one relative to the other, the result being that the intermediate gears 45 b^2 cannot turn, but act merely as keys to lock the pulley-gear a^3 and the internal gear d^2 together, so that the rotation of the pulley a is directly transmitted to the shaft. To accomplish this, it is necessary only to bring 50 the member i into engagement with the lever g and the member k into engagement with the lever e , and in accordance with the invention it is practicable to accomplish this without any additional shipper mechanism, 55 the same actuating device being used as in the ordinary slow-speed forward and reversing operations. In order that this may be accomplished, the rods i^4 and k^4 , which are normally connected together, are capable of 60 being disconnected in such a way that after 65

one of the said rods has been moved in one direction to operate one of the engaging members the said rod can be disconnected and left stationary, while the other rod is moved in the other direction by the same actuating device to operate the other engaging member. As herein shown, the two rods are mounted in a sleeve or support m , which is connected with the shipper m^2 , one of the said rods being shown as fastened at m^3 in the said sleeve, while the other rod bears against the end of the fastened rod, so as to be pushed thereby in one direction. 75

The rod k^4 is shown as connected with the sleeve or support m , to which in turn the shipper m^2 is pivoted, so that the swinging movement of said shipper will produce a longitudinal movement of the rod k^4 and the fork k^3 carried thereby. The rod i^4 extends into the sleeve or support m , so as to engage 80 the end of the rod k^4 , so that a movement of the shipper m^2 to the left will produce a longitudinal movement in that direction of both the rod k^4 and the rod i^4 , so as to slide the members k and i into engagement, respectively, with the levers f and g . The rod i^4 , however, may be disconnected from the shipper in case it is desired to leave the member i in engagement with the lever g while the member k is being moved into engagement with the lever e . To this end the rod i^4 is capable of being connected with and disconnected from the member m , the connecting means being herein shown as a latch n , having an inclined face n^2 and a shoulder n^3 to engage a corresponding shoulder in the rod i^4 . 90

When the latch n is in the position shown in Fig. 1, in which it may be held by means of a spring n^4 , the rod i^4 is connected with the sleeve m , so as to be moved therewith in either direction—as, for example, when the members i k are being moved to the position shown. The latch n , however, is under the control of the operator, being preferably 100 connected with a grip n^5 , pivoted to the shipper m^2 , near the handle thereof, so that if the shaft c is to be driven ahead at full speed the operator, by pushing the shipper to the left, will carry the member i into engagement 105 with the lever g , and by means of the grip n^5 he then disconnects the rod i^4 from the shipper, as shown in Fig. 3, so that the movement in the other direction carries the rod k^4 only, and thereby moves the member k into 110 engagement with the lever e . To change the conditions, it is necessary only to move the shipper to the left, which will disengage the member k , the rod i^4 becoming automatically 115 latched or connected to the shipper at the end of such movement, so that a subsequent movement of the shipper in the opposite direction will move the member i out of engagement with the lever g . When the latch is 120 not operated, the movement of the shipper 125

in one direction will produce the slower forward movement of the shaft, while the movement thereof in the opposite direction will reverse the shaft.

5 It is not intended to limit the invention to the specific construction and arrangement shown and described, since modifications may be made without departing from the invention.

o I claim—

1. In a shaft-reversing mechanism, the combination with the pulley; of a shaft; a sleeve interposed between said pulley and said shaft and constituting a bearing for the 5 pulley; a gear connected with the pulley; an intermediate gear connected with said sleeve; a second sleeve mounted on the shaft and provided with a gear coöperating with said intermediate gear; a stationary member; and 20 means coöperating with said sleeves for connecting either sleeve with the shaft or with said stationary member, substantially as described.

2. In a shaft-reversing mechanism, the 25 combination with a pulley; of a gear thereon; a shaft with two members mounted thereon; an internal gear on one member; intermediate gears on the other member in mesh with said internal gear and the gear on the pulley; a 30 stationary member; and means for connecting either of said members with said shaft, and the other with said stationary member to prevent its rotation; and a single device coöperating with said means.

3. The combination with a shaft; of a 35 sleeve having a bearing on said shaft; one or more intermediate gears on said sleeve; a pulley mounted on said sleeve; a gear on said pulley in mesh with said intermediate gears; a second sleeve mounted on the shaft; an 40 internal gear on said second sleeve in mesh with said intermediate gears; a stationary clutch member corresponding to each sleeve; a shaft clutch member corresponding to each 45 sleeve; clutch members connected with each sleeve to coact respectively with the clutch members aforesaid; actuating members, one for each sleeve, interposed between the clutch members thereon to actuate one of 50 them by a movement in one direction, and the other by a movement in the other direction; and a single actuating device for said

clutch-operating members, substantially as described.

4. The combination with the shaft; of two 55 clutch members connected therewith; two sleeves having corresponding clutch members, an internal gear on one of said sleeves; one or more intermediate gears carried by the other sleeve; a pulley loosely mounted on one 60 of said sleeves; a gear on said pulley in mesh with the intermediate gears; stationary clutch members and clutch members mounted on the sleeves to engage said stationary clutch members respectively; longitudinally- 65 movable clutch-operating members; actuating-rods for said clutch-operating members; a shipper connected with said rods; and means for disconnecting said shipper from one of said rods but not from the other, substantially 70 as and for the purpose described.

5. In a reversing and speed-changing mechanism, the combination with two longitudinally-movable clutch-operating devices; of two clutch members for each operating device, the said operating devices being located between the said clutch members; a shipper-rod made in two parts, one part being connected with one operating device and the other part with the other operating device; a 80 shipper connected with one of the said rods; and a locking device for connecting the said rods together whereby both are operated by the same movement of the shipper, as set forth.

6. In a reversing and speed - changing mechanism, the combination with two clutch-operating members and clutches operated thereby; of a shipper provided with a support; a rod connected with one clutch-operat- 90 ing member and also with said support; a rod connected with the other operating member and supported in said support; a latch co-operating with the rod last named; and an actuating device for said latch connected with 95 the shipper, as set forth.

In testimony whereof I have signed my name to this specification in the presence of two subscribing witnesses.
